UNITED STATES PATENT OFFICE.

HALBERT K. HITCHCOCK, OF PITTSBURGH, PENNSYLVANIA, ASSIGNOR OF ONE-HALF
TO JOHN F. JOHNSON, OF PITTSBURGH, PENNSYLVANIA.

DOOR-HOLDING DEVICE.

1,305,212.

Specification of Letters Patent. Patented May 27, 1919.

Application filed July 12, 1918. Serial No. 244,527.

To all whom it may concern:

Be it known that I, HALBERT K. HITCHCOCK, a citizen of the United States, and a resident of Pittsburgh, in the county of Allegheny and State of Pennsylvania, have made a new and useful Invention in Door-Holding Devices, of which the following is a specification.

The invention relates to attachments for doors, and particularly for doors for use on motor vehicles, in which the vibration of the machine frequently causes rattling and squeaking. A door which does not fit tightly is liable to rattle due to the vibration, while a tight fit is difficult to secure and is liable to cause squeaking when the engaging surfaces move past each other slightly. The primary object of the present invention is to provide a device which will 20 rigidly support the free end of the door when closed upon relatively large wearing surfaces, with the parts so arranged that the surfaces will be brought into engagement or disengaged with a minimum amount 25 of friction, thus reducing the wear and effort necessary to move the parts, and insuring that the parts will remain in adjustment during the life of the door. Further objects 30 of the invention are to provide a device in which breakage is avoided, which rigidly supports the door against any downward movement whatever, which relieves the hinges of the wear incident to the vibration of the machine, and which applies 35 yielding force tending to open the door and keep this door latch or lock tight.

Certain embodiments of the invention are illustrated in the accompanying drawings wherein Figure 1 is a perspective view showing the application of one part of the device to the door jamb, Fig. 2 is a perspective view showing the application of the other part of the device to the door, Fig. 3 is a transverse section on the line III—III of Fig. 6, Fig. 4 is a face view of part of the device shown in Fig. 1 with the cover plate removed, Fig. 5 is a section on the line V—V of Fig. 4, Fig. 6 is a view similar to Fig. 4 with the wedge portion of the device shown 50 in section in an operative position, and Fig. 7 is a face view of a modification of one of the parts of the device, the holding screw for the adjusting spring being shown in section.

Referring to the part of the device shown

in Fig. 1, the reference numeral 1 indicates the door jamb in which is seated the casing 2, such casing being closed by the plate 3, secured to the casing by means of the screw 4. The screws 5 engage the door jamb and serve to secure the casing in position. The door 6 is provided with a plate 7 secured in position by means of the screws 8 and carrying the wedge or spreader member 9. The plate 7 and the casing 2 are so positioned relatively that when the door is closed the wedge 9 enters the slot 10 (Fig. 1). The door jamb is provided with the usual overlapping strip 11, while the door is provided with a corresponding strip 12 (Fig. 3).

Mounted in the casing 2 are a pair of toggle plates 13 and 14, such plates having cylindrical bearing portions 15 at their ends which engage corresponding recesses in the ends of the casing. The plates are mounted 75 so as to swing back and forth and are yieldingly held in forward position by the leaf spring 16. The upper plate 13 is provided with a projecting pin 17 and on this pin is mounted a relatively stiff spring 18, the upper end of which is held in a slot 19 in the plate, while the lower portion 20 constitutes a bearing surface as hereafter set forth. The lower plate has a projecting flange 21 whose upper surface constitutes a bearing 80 surface in opposition to the spring portion 20. The two plates are curved at their meeting edges 22, and roll on each other when the plates are moved in and out. The plates are thus securely held in position until the 90 cover plate of the casing is removed, at which time the plates may be removed by lifting them out of the casing.

In operation, the closing of the door brings the wedge 9 into the space between the opposing bearing members 20 and 21 as indicated in Fig. 6. The spring 16 serves to keep the plates in the proper position to receive the wedge 9, and by resisting the inward movement of the plates and applying pressure on the wedge tends to open the door. This application of pressure holds the latch of the door-lock tight and prevents any swinging movement of the door upon its hinges. As a result there is no rattling of the door or the lock such as ordinarily occurs when lost motion is present after the latching of the lock. The wedge 9 is also firmly but yieldingly clamped or held between the opposing bearing members 20 and 100 105 110

bearing members arranged to receive the spreader member between them and apply an increasing pressure thereto at right angles to the plane of movement of the spreader member as the door member moves to closed position, and spring means permitting the spreader member to move vertically in one direction.

5. In combination in a door holding device adapted to coöperate between a horizontally swinging door member and a jamb member, a spreader member adapted to be carried by one of the members, a pair of bearing members arranged to receive the spreader member between them and apply an increasing pressure thereto at right angles to the plane of movement of the spreader member as the door member moves to closed position, and spring means permitting the spreader member to move vertically in one direction, the support of the spreader member in the reverse direction being unyielding.

6. In combination in a door holder for use between a door member and a jamb member, a tongue carried by one of said members, a pair of opposing plates pivoted to the other member so as to approach as they move to the rear and having bearing faces in position to receive the tongue between them, and having the bearing face of one plate flattened, and spring means for holding the plates in advanced position, the said faces being inclined toward each other and adapted to roll over the opposite faces of the wedge as the plates are carried to the rear by the tongue until the wedge engages the flattened portion of said face.

7. In combination in a door holder for use between a door member and a jamb member, a tongue carried by one of said members, a pair of opposing toggle plates pivoted to the other member and having bearing faces in position to receive the tongue between them, means for holding the plates yieldingly in advanced position, and spring means permitting the movement of one bearing face away from the other.

8. In combination in a door holder for use between a door member and a jamb member, a tongue carried by one of said members, a pair of opposing toggle plates pivoted to the other member so as to approach as they move to the rear and having bearing faces in position to receive the tongue between them, and means for holding the plates yieldingly in advanced position, one of said bearing faces being yieldably mounted for movement transversely of the path of movement of the tongue.

9. In combination in a door holder for use between a door member and a jamb member, a tongue carried by one of said members, a pair of opposing toggle plates pivoted to the other member and adapted

to approach as they move to the rear and having bearing faces in position to receive the tongue between them, one of said faces being spring supported, and the other rigidly supported, and means for holding the plates yieldingly in advanced position.

7. In combination in a door holder, a casing for mounting on the door or jamb member, a pair of toggle members mounted in the casing having opposing bearing faces and adapted to move back and forth in the casing, with the bearing faces approaching each other as the members move to the rear, means for yieldingly holding the said pair of members in advanced position, yielding means whereby one of said bearing faces may move away from the other while such other face is held rigidly in position, and a tongue member for mounting on the other door or jamb member, and adapted to enter the space between said bearing faces and engaging such faces.

8. In combination in a door holder, a casing for mounting on the door or jamb member, a pair of toggle members mounted in the casing having opposing bearing faces, one of which is flattened, arranged to move back and forth in the casing on curved paths and approach each other as they move back, means for yieldingly holding the pair of members in advanced position, yielding means whereby one of said bearing faces may move away from the other, and a tongue member for mounting on the other door or jamb member and adapted to enter the space between said bearing faces, engaging them with rolling friction, as it moves the said pair of members to the rear in the casing, the said tongue when in extreme rear position engaging the said flattened face.

9. In combination in a door holding device adapted to coöperate between a swinging door member and a jamb member, a spreader device adapted to be carried by one of said members and a coöperating device adapted to receive the spreader device and carried by the other member, said device including toggle means tending to open the door and to apply yielding pressure to the upper side of the spreader tending to hold the free edge of the door against upward movement, while rigidly holding it against downward movement.

10. In combination in a door holding device adapted to coöperate between a swinging door member and a jamb member, a spreader device adapted to be carried by one of said members, and a coöperating device adapted to receive the spreader device and carried by the other member, said device including toggle means and spring means applying pressure tending to open the door and spring pressure tending to prevent upward movement of the spreader.
